UNITED STATES PATENT OFFICE

2,488,866

GRINDER MACHINE ACCESSORY

Louis Ilmer, Cortland, N. Y.

Application February 2, 1946, Serial No. 645,180

11 Claims. (Cl. 51—150)

1
My invention relates to novel improvements in surface grinding machinery, and is more particularly concerned with abrading a long batch length of reelable alloy steel or the like elongated stock by the use of abrasive tape. Said machine is adapted to drag its work piece from a suitable stock storage agency in a directed travel path that extends through my grinder unit to rapidly and economically pregrind such work piece lengthwise in successive passes, the strip travel rate of itself furnishing the necessary velocity for intensive cutting action upon having relative coarse grit applied thereto.

The present grinder unit is devised to utilize slowly fed paper-backed grit in roll tape form, the performance being such as to expend its grit life in a single pass through a localized cutting zone. Because of a progressive grit loading, the emerging ground metal strip may in one treatment be given a lustrous or virtually burnished finish.

A tape supply spool and a corresponding driven offtake reel may feed multiple comparatively narrow tapes through their respective cutting zones when such tapes are distributed edgewise across the entire strip width. Simple motorized means are provided for slowly driving such offtake reel and for facilitating a speedy replenishment of tape renewal.

The object of my invention is to devise a refined grinder unit of the indicated character adapted to abrasively treat a long batch length of reelable stock on a rapid low cost production basis. Embodied herein are diverse tape control improvements that promote the end in view.

Reference is had to the accompanying three sheets of drawings which depict an illustrative embodiment, and in which:

Fig. 1 shows a top plan view of my grinder unit; and Fig. 2 diagrammatically represents an elevational side view of such assembly taken obliquely along the section 2—2 of Fig. 1.

Fig. 3 represents a sectional view of my improved tape supply spool equipped with an in-built braking device as taken along 3—3 of Fig. 1; and Fig. 4 is a cross-sectional view taken along 4—4 of Fig. 3.

Fig. 4A details certain tape securing means.

Fig. 5 presents a sectional view of my takeoff reel along line 5—5 of Fig. 1.

Fig. 6 is fragmentally taken along 6—6 of Fig. 5 to show a pin gear mechanism for intermittently advancing the tape supply; and Fig. 7 is an elevational side view of such assembly.

Referring more specifically to these disclosures, my grinder unit preferably comprises a rotor drum 10 affixed upon the axle 11 that spans the opposed housing girders 12 and 13 in the Fig. 1 manner. The rotor rim ends are purposely flanged

as at 14 and the rotor may be perimetrically lagged at 10A with a rubber sheath (see Fig. 2).

The motorized rotor axle 11 may be coupled at 16 to a suitable prime mover whereby to drag the work piece 17 in a directed travel path. The rotor may be driven in the arrowed direction to impart a desired linear velocity to said work piece. Such work piece may comprise a single endless loop of stock or multiple strips of finite length laid alongside each other to fall within the confines of the overall tape width marked W (see Fig. 1).

A guide pulley 18 may divertingly direct the surplus strip stock coming from a suitable magazine or storage agency onto the rotor perimeter as shown in Fig. 2. The out-turned face of the treated strip 17 may be simultaneously preground by a plurality of abrasive paper-backed roll tapes, respectively mounted upon the twin supply spools or drums 20 and 21. The overall tape width of each such tape supply quota is preferably split up into aliquot components W' that are kept closely spaced edgewise. The non-overlapping tape groups of finite length such as 20T and 21T 25 may respectively be slowly fed into their cutting zones in an obliquely inclined direction to the rotor axis (see Fig. 1). For a relatively large rotor diameter, the cutting zone length as measured perimetrically, may be kept comparatively long and thus maintain a biased ridge-free cutting lap between each inclined next adjacent tape interspace.

The housing girders 12 and 13 may further be spanned by the parallel trunnion shafts 22 and 23. Affixed to the respective end regions of each such shaft, are the guide levers 24 and 25 of which corresponding free extremities may be bridged by a header beam such as 26 or 27. These beams are rendered selectively shiftable toward or away from the rotor axis. For this purpose, corresponding ends of each trunnion shaft may be equipped with a worm gear 28 and a worm 29 that are adjustable in unison through a worm connection shaft 30.

45 Each header beam may pivotally carry one or more spring backed shoes 19 placed in tandem and respectively having a length equal to the tape width W'. A spring encasing tubular slide 31 may floatingly back the associated shoe thereof. Such backing thrust as applied to a suspended medial tape region, is preferably kept under moderate intensity per square inch of grit contact area and collectively arranged to extend uniformly across the entire strip width W, irrespective of 50 the accompanying beam deflection.

The tape offtake reels 32 and 33 may respectively be provided with parallel spindles 34 and 35 that are given an acutely oblique inclination with respect to the rotor axis. As detailed in Fig. 5, 55 each such hollow cylindrical reel may be flanged

and have its spindle mounted in frame supported bearings. One spindle end is shown provided with a coupling 36 of which the adjoined members may be interlocked by the demountable key 31.

The spindles 38 and 39 of the respective tape supply spools 20 and 21 are preferably disposed in a trailing parallel relation to their respective reel spindles in the Fig. 2 fashion. The cylindrical rim diameter of such set of drums may be kept equal and sufficient in size that a standard 50 yard roll of abrasive tape when mutually coiled thereon in suspended relationship as shown, may be transferred without building up excessive convolutions on either drum. Such disposition permits of maintaining a virtually uniform tape feed rate for a constant takeoff reel speed.

As guided by certain rollers, the path and feed direction of each suspended tape 20T and 21T are indicated by dotted outline in Fig. 2, the dragged tape being purposely headed downwardly toward the yoked spindle supporting crotch 50'. The coiled tape grit is preferably exposed exteriorly on the respective drums 32 and 33 where it may readily be inspected for proper performance. It will be observed that virgin tape preferably enters its cutting zone beneath a backing shoe in the direction of rotor rotation. Since my slowly fed tape is intended to become substantially spent prior to leaving its cutting zone, even coarse grit loads sufficiently to impart a virtually burnished finish to the work piece after being treated in successive passes. The described dual header beams serve to double the rate of stock removal, it being evident that a single header unit might likewise be used.

When the abrasive is fed as indicated, the resulting cutting plus frictional drag tends to strip the supply spool of tape. To counteract such stripping, it is preferred to compactly inbuild a relatively powerful slip clutch unit into each supply spool (see Fig. 3). One or both ends of my sleeve-like tape supply drums such as 20 may be counterbored for the reception of the reversely disposed companion slip rings 42 and 43, these being recessed to center therebetween multiple helical compression springs such as 44.

Said rings respectively thrust against the clutch plates 45 and 46 provided with interspaced hubs mounted upon a common spindle 38. Plural plate clamping bolts 47 are disposed radially inward of the clutch rings to retain the springs under compression. The use of shims (not shown) allows the frictional clutch to be adjusted to suit drag requirements. The hubs of the plates 45 and 46 are preferably keyed at 48 to the speed controlled spindle 38 while the plate perimeter slides freely in the drum counterbore. On the other hand, the perimeter of the rings 42 and 43 may each be keyed at 49 to the supply drum 20 to effect a frictional drag between each plate and its slip ring when the spool sleeve is rotated with respect to the restrained spindle.

Each frame supported bracket such as 50 may be forked or given a like yoke shape at its upstanding end 50' to demountably journal the spindle 38 therebetween for unitary removal of my brake equipped tape spool. One spindle end may be provided with separable spur gears 51 and 52 arranged to be intermittently driven by a so-called ratiomotor unit comprising the worm reduction gear 53 and a worm 54 directly connected to the armature shaft of a small motor M-1. When this motor is inoperative, the worm 54 automatically stalls the spindle 38 but permits the spool 20 to rotate thereon while subjected to clutch braking drag. The tape counterdrag imposed by

the adjusted clutch springs is intended to exceed the cutting drag exerted on the shoe loaded tape by the revolving rotor 10 and hence requires a substantial differential drag effort on part of the companion offtake reel to effect tape transfer. The perimeter of the spool 20 and that of the reel 32 may each be longitudinally kerfed as at 56 to respectively engage a hookshaped strap 57 attached to each tape end in the manner detailed in Fig. 4A.

Referring now to Figure 5, this discloses the preferred mode for slowly driving my offtake reel 32. Mounted upon an overhanging bracket 58, is a so-called large-range gyro speed reducer comprising the tubular casing 59. Through the casing axis there extends a high speed input shaft 60 provided with an eccentric length 61 upon which is mounted a dual gyro gear 62 of the spur gear type. A stationary internal gear 63 meshes with one such spur gear and the other spur gear may mesh with the movable internal gear 64 keyed to the slow speed output shaft 65. The coaxial stationary and movable internal gears 63-64 are respectively provided with more teeth than their mated dual gears 62 whereby the eccentric movement imparted to the latter causes a slow advancement of the output shaft 65.

The inherent disadvantage of an equivalent double reduction worm gear unit affording a commensurate speed reduction, lies in its defective worm behavior due to inadequate lubrication when running at the extremely slow output duty herein required. The more compact spur gearing of the cited gyro unit does not suffer from a like limitation.

In order to adapt said gyro drive to present needs including the provision for tape feed regulation, it is preferred to snugly superimpose a controlled reducer mechanism upon the casing 59 in the Fig. 5 manner. To this end, I may resort to a motorized twin tooth pinion as embodied in the oppositely disposed cam lobes 67 and 68. The similar non-circular profiles thereof are respectively shaped to smoothly pick up and periodically advance in actuated ratchet fashion, a pin roller type of gear arranged to drive the gyro input shaft 60.

As detailed in Figs. 6 and 7, said drive mechanism may be installed in a demountable frame 69 provided with a pinion shaft 70 and a supplementary gear shaft 71 that respectively lie in parallelism with the input shaft 60. Said pinion shaft is coupled at 72 to the speed reducer 73 of the ratiomotor type comprising the worm gear 74 that is driven by the constant speed fractional H. P. motor M-2.

The gear shaft 71 mounts three laterally spaced pin-connected discs 76A, 76B and 76C. For a speed reduction of 6:1 as shown, each next adjacent pair of discs may be bridged by six pin rollers such as 77 or 78 which are relatively staggered about the shaft 71 to constitute a pin gear. The camlike lobes 67 and 68 respectively align with one set of such rollers and mesh therebetween.

In the Fig. 6 layout, one rotating lobe 68 has been brought into engagement with its roller 78 while the other trailing lobe 67 is about to engage a contiguous roller 77 to apply torque that progressively rotates the gear shaft 71 stepwise in its arrowed direction. The lobe 68 has about reached the limit of its stepwise gear throw and hence may be made to establish a short dwell period prior to the time that the lobe 67 picks up its roller 77. Each cam profile is shaped to non-interferingly enter successive pin rollers 76 thereof and thus permit a rapid frequency rate

between successive dwell periods without abnormal shock effects.

One end of the gear shaft 71 and a corresponding end of the gyro input shaft 60 are respectively provided with mated change gears 80 and 79 whereby to conveniently alter the rate of tape transfer to meet different cutting conditions. Save for lobe clearance, the worm gear reducer 73 stalls the gear shaft 71 against inadvertent reversal.

As regards the intended mode of tape replenishment, each restocked supply spool 20 or 21 may initially have wound thereon a full quota of fresh tape of which the bottom tape end may be cleated in place as in Fig. 4A. By bodily lifting an exhausted tape supply spool together with its clutches out of the spaced bracket yokes 50, another supply spool with virgin tape may be substituted in its place. The outer tape end thereof may by splicing be trailingly dragged through a Fig. 2 tape path and hooked into the kerf 56 of its previously emptied offtake reel. After such fresh tape supply has in turn become exhausted, the coupling key 31 may be withdrawn to permit unobstructed rotation of an associated offtake reel. By then starting the motor M-1, the spent tape will back-track onto its original supply spool for tape removal purposes. Such motorized back tracking of a long tape length speeds up the daily productive capacity of my strip grinder by minimizing the servicing time otherwise needed on part of skilled labor when manually transferring such tape.

The foregoing rather explicit disclosure will, it is believed make evident to those skilled in this art, the more outstanding commercial and operative advantages afforded by my tape feed refinements, it being understood that I reserve the right to correspondingly modify my single illustrative embodiment, all without departing from the spirit and scope of my invention heretofore described and more particularly defined in the appended claims.

I claim:

1. A grinder machine adapted to treat elongated stock, as a work piece and which machine comprises driven drag means to move the work piece longitudinally in a directed travel path; an abrasive tape of finite length operatively applied to said work piece in a localized cutting zone, a tape supply spool and a mated takeoff reel of which the respective axes are parallelly disposed with a medial tape portion transferably suspended therebetween; a spindle mounting the supply spool thereon; braking means for the supply spool including a clutch plate member and a spring loaded frictional slip ring member that spacedly encircles the spool spindle and one of which members is fixed to the supply spool and the other member is fixed to said spindle; a clamping bolt entered through such spacing and serving to retain the ring in loaded engagement with said plate; and drive means for rotating the takeoff reel.

2. A grinder machine adapted to treat elongated stock as a work piece and which machine comprises driven drag means to move the work piece longitudinally through a directed travel path; an abrasive tape of finite length, said tape being operatively applied to the work piece in a localized cutting zone, a tape supply spool having a tubular rim, a spindle rotatably mounting said spool, a cooperative takeoff reel having its axis disposed in substantial parallelism with that of the spool and a medial tape portion trans-

ferably suspended therebetween, and frictional braking means for the supply spool including a clutch plate affixed to the spool spindle and slip fitted with respect to said rim and further including a cooperating slip ring affixed to the spool rim in an encircling relation to said spindle; means for axially impressing said ring into flatwise frictional engagement with its plate, and means for controllably retaining the spindle against rotation.

3. A grinder machine adapted to treat elongated stock as a work piece and which machine comprises driven drag means serving to move the work piece longitudinally through a directed travel path; an abrasive tape of finite length, said tape being operatively applied to the work piece in a localized cutting zone, a tape supply spool and a mated offtake reel of which the respective axes are disposed in substantial parallelism with a medial tape portion transferably suspended therebetween; a spindle rotatably mounting said spool thereon; braking means for the supply spool comprising a pair of frictionally coupled clutch members of which one is affixed to rotate in unison with the spool spindle and the other member is affixed to rotate in unison with the supply spool, and motorized drive means for said spool spindle including a locking agency that automatically stalls the spindle against rotation when said drive means is rendered inactive.

4. A grinder machine adopted to treat elongated stock as a workpiece and which machine comprises means for dragging the work piece longitudinally through a directed travel path, an abrasive tape of finite length; said tape being operatively applied to the work piece in a localized cutting zone, a tape supply spool and a mated offtake reel of which the respective axes are parallelly disposed with a medial tape portion transferably suspended therebetween; a spindle rotatably mounting said spool thereon; braking means for the supply spool comprising a pair of frictionally coupled clutch members of which one is affixed to the spool spindle and the other member is affixed to rotate with the supply spool, motorized drive means for said spool spindle including a locking agency that stalls the spindle against rotation when said drive means is rendered inactive; another drive means for rotating the offtake reel; a disengageable coupling for the last named drive means, said coupling when disengaged allowing previously transferred tape to back track on to the supply spool.

5. A grinder machine adopted to treat elongated stock as a work piece and which machine is equipped with driven drag means serving to move the work piece longitudinally, an abrasive tape of finite length of which a medial portion is operatively applied to the work piece in a localized cutting zone, a pair of rotatable drums disposed in substantial parallelism and respectively having said tape wound about such drums in a spanning transferable relationship, and a tubular casing mounting therein a stationary internal gear, a gear driven slow speed output shaft and a motorized axially aligned input shaft provided with an eccentric upon which is mounted interlocked dual spur gears of which one such meshes with the output shaft gear and the other meshes with the stationary gear to provide for a long range speed reduction between said shafts, said output shaft being coupled to slowly rotate one of the aforesaid drums and thereby feed the abrasive tape at a rate by which its grit becomes

substantially spent in one pass through said cutting zone.

6. A grinder machine adapted to treat elongated stock as a work piece and which machine is equipped with driven drag means serving to move the work piece longitudinally, an abrasive tape of finite length of which a medial portion is operatively applied to such work piece in a localized cutting zone, a pair of rotatable drums disposed in substantial parallelism and respectively having said tape wound about such drums in spanning transferable relationship, a speed reducer mounting a high speed input shaft and a slow speed output shaft, the latter being coupled to one of said drums, a reducer drive mechanism including a pinion shaft provided with opposed camlike lobes and further including a supplementary gear shaft carrying a pin gear thereon that cooperatively meshes with said lobes, said gear shaft being arranged to drive the aforesaid high speed shaft, and motorized means for rotating said pinion shaft.

7. A grinder machine adapted to treat elongated stock as a work piece and which machine is equipped with driven drag means serving to move the work piece longitudinally, an abrasive tape of finite length operatively applied to such work piece in a localized cutting zone, a rotatable tape supply drum and a mated offtake drum having a medial tape portion transferably suspended therebetween, a speed reducer mounting a high speed input shaft and a slow speed output shaft, the latter being coupled to one of said drums, a reducer drive mechanism, comprising a rotatable pinion shaft and a supplementary shaft mounting a pin gear thereon, the pinion shaft having two axially interspaced camlike lobes set in radial opposition and the pin gear comprising multiple laterally spaced discs of which one pair of next adjacent discs are pin interconnected in staggered relation to the pins of another pair of such discs to successively mesh with the respective lobes, and motorized means for rotating the pinion shaft and which supplementary shaft is arranged to drive the aforesaid input shaft.

8. A grinder machine adapted to treat elongated stock as a work piece and which machine is equipped with driven drag means serving to move the work piece longitudinally, an abrasive tape of finite length operatively applied to such work piece in a localized cutting zone, a pair of rotatable drums disposed in substantial parallelism and respectively having said tape wound about such drums in spanning transferable relationship, a tubular speed reducer casing mounting therein an outwardly projecting input shaft and an axially aligned slow speed output shaft coupled to one of the drums, a reducer drive mechanism superimposed upon said casing and including a motorized pinion shaft provided with camlike lobes and further including a supplemental gear shaft disposed in parallelism with the casing axis to carry a pin gear thereon that cooperatively meshes with said lobes, and change gear means operatively interconnecting corresponding ends of the supplemental gear shaft and said input shaft.

9. A grinder machine adapted to treat elongated stock as a work piece and comprising drag means adapted to move the work piece longitudi-

nally in a directed travel path, an abrasive tape of finite length operatively applied to the work piece in a localized cutting zone, a rotatable tubular tape supply spool of which the ends are respectively provided with an axially projecting journal, braking means inbuilt into said spool to comprise a pair of laterally spaced clutch plate members that are each interiorly engaged by a separate slip ring member having compression springs interposed between said rings and means rotating one pair of like members in unison with a journal and for rotating the other pair of like members in unison with the supply spool, said braking means being bodily demountable as a unit with the spool.

10. A grinder machine adapted to treat strip stock as a work piece and which machine is equipped with a motorized rotor having a work piece portion belted to the rotor rim and serving to longitudinally move the work piece in the rim travel direction, an abrasive tape of finite length operatively applied to the outer side of the work piece to constitute a localized cutting zone thereon, a tape backing shoe superimposed upon such zone and impressing tape grit inwardly toward the rotor axis to subject the tape to a cutting drag, a rotative tape supply spool and an associated tape offtake reel having an interposed tape portion transferably suspended therebetween in an acutely oblique inclination with respect to the aforesaid travel direction, brake means for the supply spool imparting a counter-drag thereon when rotated, and drive means slowly rotating the offtake reel to advance the suspended tape portion through said zone against the counter-drag imposed upon the supply spool whereby to obviate stripping tape off of such spool by the cutting drag.

11. A grinder machine equipped with driven rotor means adapted to drag an elongated work piece longitudinally in a certain travel direction, an abrasive tape operatively applied to the work piece to constitute a cutting zone which tends to draw along such tape in the aforesaid travel direction, a tape supply spool and a mated offtake reel disposed in substantial parallelism with a portion of such tape transferably extending between said spool and reel, slip clutch means operatively associated with the spool and imposing a dominating brake counter torque thereon superior in magnitude to the drag tendency of the tape cutting zone, and dual cam lobes together with a cooperating pin gear serving to intermittently actuate the reel in close succession and feed said tape off the spool onto the reel.
